MARINE STEERING WHEEL HOUSING BRACKET

John H. Whitehouse, Springfield, Mass., assignor to
Custom Marine Equipment Corp., Springfield, Mass., a
corporation of Massachusetts

Application September 22, 1954, Serial No. 32,393

Term of patent 14 years

(Cl. D14—30)

Fig. 3

Fig. 4

Fig. 1

Fig. 2

Figure 1 is a side elevational view of a marine steering wheel housing bracket showing my new design;

Figure 2 is a top plan view thereof;

Figure 3 is a front perspective view of the bracket element; and

Figure 4 is a rear perspective view of the bracket and steering wheel.

The steering wheel and drum member disclosed by means of broken lines are shown only for illustrative purposes.

I claim:

The ornamental design for a marine steering wheel housing bracket, substantially as shown and described.
